RAILWAY SIGNALING APPARATUS

Lars O. Grondahl, Pittsburgh, Pa., assignor to
The Union Switch & Signal Company, Swiss-
vale, Pa., a corporation of Pennsylvania

Application May 17, 1935, Serial No. 22,052

4 Claims. (Cl. 246—41)

My invention relates to railway signaling apparatus, and more particularly to apparatus of the type involving track circuits.

One of the objects of my invention is to provide 5 novel and improved means to insure the release of a track relay when a vehicle or train enters the associated section.

The apparatus for insuring the release of a track relay set forth in the present application 10 is somewhat similar to that set forth in my copending application Serial No. 705,558, filed on January 6, 1934, for Railway track circuit apparatus, and the said copending application contains claims which cover broadly certain features 15 of the invention described in my present application.

In the accompanying drawing, Figs. 1 to 8, inclusive, show various forms of track circuits each embodying my invention.

20 Similar reference characters refer to similar parts in each of the several views.

Referring first to Fig. 1, the reference characters $1a$ and $1b$ designate the rails of a stretch of railway track, which rails are divided by insulated joints 10 to form track sections, only one of which is shown in the drawing and is designated A—B. The track section A—B is provided with a track circuit including a track relay TR connected across the rails $1a$ and $1b$ at one end of the section in series with a microphone M, and a track battery 3 connected across the rails $1a$ and $1b$ at the other end of the section. The microphone M is of the type which increases its resistance when a train passes over the track rail to 35 which it is attached. A microphone of this type is fully disclosed in Patent No. 1,834,077, issued December 1, 1931, to A. J. Sorensen.

When a train moving in the direction indicated by the arrow enters the section A—B, the vibration of track rail $1a$, caused by the train as it passes the microphone M, causes the microphone to vibrate and its resistance to increase at the same time that the track rails are being shunted, thereby insuring the release of the track relay 40 TR. Once the track relay TR has released its armature, a less effective shunt than that required to release the relay without the assistance of the microphone will be sufficient to prevent the track relay again picking up after the resistance of the microphone is again reduced to its normal value. When the train clears the section, the relay TR again picks up in the usual manner.

In Fig. 2, the track relay TR, instead of being connected to rails $1a$ and $1b$ in series with the 45 microphone M, is connected in series with nor-

mally closed contacts of an auxiliary relay A1; and the latter relay is normally energized over a local circuit in series with the microphone and an auxiliary battery D. The use of the auxiliary relay makes it possible to design the relay to match 5 the microphone and also removes the microphone resistance from the track relay circuit. When a train enters the section and passes the microphone, its resistance increases to a point where the relay A1 can no longer hold its contact 10 closed. It will be apparent, therefore, that whether the train efficiently shunts the track relay or not it will be caused to release.

In the form of the invention covered by Fig. 3, the track circuit at the relay end includes the 15 microphone M, the track relay TR, and a balancing resistance 16.

The potential of the battery 3 is greater than ordinarily employed, but with that portion of the electromotive force in excess of that normally 20 employed balanced out by an auxiliary electromotive force so that a smaller fractional change in the voltage at the entering end of the track circuit is required to effect release of the track relay than ordinarily required. The auxiliary 25 circuit extends from the positive terminal of battery D through resistance 18 to the lower terminal of resistance 16, where it joins the track circuit path to the one terminal of the track relay; and from the negative terminal of battery 30 D through the balancing resistance 15 at the upper terminal of which it joins the track circuit path to the other terminal of the track relay. The values of resistances 15 and 16 are such that with proper setting of the adjustable resistance 35 18 the electromotive force of the track circuit across the terminals of resistance 15 will exceed that of the auxiliary circuit by the potential required to pick up the relay.

For example, if the track relay requires two 40 volts across its terminals to pick it up, the difference in potential required across resistance 15, between the track and auxiliary circuit, will be two volts while the actual potential of each of the respective current sources 3 and D may be 45 much higher. If now we assume that the relay will release when the potential across its terminals is reduced to one volt, then in the conventional track circuit this will represent a requirement of a 50% drop in voltage to effect release of 50 the track relay. With the circuits herein provided the energization of the relay is effected by two volts, and the drop in voltage required to effect the release of the relay is one volt as before. However, the track circuit potential avail- 55

able at the relay may, for example, be ten volts and that of the auxiliary circuit, eight volts in the opposing direction. Under these conditions, the relay is energized by a potential of two volts, as before, but a less efficient track shunt, effective to obtain a 10% drop in potential will cause the required one volt decrease in potential required to effect release of the track relay.

In order to retain a constant relationship between the current flowing through the track relay from source D with respect to that supplied over the track circuit, ground electrodes 11 and 12 are connected in shunt of the battery D. These electrodes are so positioned with respect to the section A-B that their shunting action on the current supplied to relay TR will be similar in its behavior with respect to changes in weather conditions to that of the ballast leakage resistance across the rails of the section on the current supplied to relay TR over the track circuit under the same weather conditions.

If the shunt placed across the rails by the train at any time becomes of sufficiently low resistance, the current flow from source D may be augmented sufficiently, by the additional current which will then flow to the relay through microphone M and the wheels and axles of the train in multiple with resistance 15 to effect operation of the relay. Under such a circumstance however, the polar contact included in the controlling circuit of the relay opens and prevents premature closure of the controlling circuit resulting from the closure of its neutral contact. If desired, a neutral relay may be employed instead of a polarized relay. In such case, the resistance values and operating characteristics of the relay must be adjusted in such manner that with an efficient shunt across the track rails the current supplied to the relay from source D will still be insufficient for picking up the relay. In either of the foregoing forms of the invention, when a train clears the section current flow in the normal direction is reestablished and accordingly the relay picks up its neutral armature. Also, in the case where a polarized relay is employed, should its polar contact have been reversed, such contact is also restored to its normal position.

In Fig. 4, the principles employed in the preceding figure are shown in the form they take when alternating current is employed. In this figure the secondary S of a transformer T supplies operating current to the rails 1a and 1b at the exit end of the section. At the entrance end of the section, the alternating current track relay is energized from the secondary S2 of a transformer T1. The transformer T1 has two primary windings. The winding P1 receives current from the secondary S3 of a transformer T2 in series with a choke coil 20. The transformer T2 has its primary winding connected to an alternating current source in reverse relation to the connection of the primary winding of the transformer T so that the current supplied to the primary winding P2 is at any instant substantially 180° out of phase with respect to that supplied to the primary winding P1. The current flow through winding P1 is, however, restricted sufficiently by choke coil 20 to enable the winding P2 to induce sufficient current in the secondary winding S2 to pick up the track relay when the section is unoccupied. When a train enters the section, the current flow through the winding P2 is readily reduced sufficiently by the shunting action of the wheels and axles of the train and decrease of current required to effect the increase

in the resistance of the microphone M to obtain the release of the track relay.

As in the direct current circuit application, provisions are made for as nearly as possible compensating for the effect variations in weather and moisture ballast conditions have on current flow through winding P2 by connecting one terminal of winding P1 to a ground electrode 21 direct and the other terminal thereof to a ground electrode 22 through inductance 23 and resistance 24, respectively. These ground electrode connections are positioned as explained in connection with the description of Fig. 3, and in a similar manner maintain the relationship between the two primary windings P1 and P2 the same irrespective of variations in ballast conditions.

It may further be explained that variable inductance and resistance elements 23 and 24 enable the characteristic of the leakage path for current flowing through winding P1 to be adjusted to closely simulate that of the ballast leakage path of the current flowing through winding P2, while the value of choke coil 20 is such that with no current flowing through winding P2, that flowing through P1 will be insufficient to operate the relay.

In the form of the invention illustrated in Fig. 5, the track relay TR is again of the alternating current type and is connected across the rails 1a and 1b in series with a contact of the auxiliary relay A1. The auxiliary relay in this instance is held energized by battery D connected to rail 1b and to the corresponding rail of the adjacent section, separated by the insulator 10.

As a vehicle enters the section a front wheel thereof momentarily bridges the upper rail joint 10 at location B and thereby shunts current from the relay A1 which accordingly drops and opens the circuit of the track relay. The vehicle, while in the section, also maintains a shunt across the rails 1a and 1b until the train clears the section. Once the track relay has released its armature, the shunting action of the train will ordinarily be sufficiently effective to prevent the track relay again picking up until the train clears the section.

The arrangement of Fig. 6 differs from that of Fig. 5 only in that the section junctions are staggered and the auxiliary battery D is connected across the opposite rails of adjacent sections. The auxiliary relay A1 will accordingly deenergize as the train enters the section and remain deenergized so long as a portion of the train occupies the space between the junctions of adjacent sections. After the train clears the junction the usual shunting action of the train will come into play to prevent the picking up of the track relay until the train clears the section.

In the form of the invention illustrated by Fig. 7, the usual battery feed arrangement, as illustrated in Figs. 1, 2 and 3, is employed. The track relay is also of the conventional type and is connected across the rails 1a and 1b at the entrance end of the section in series with a photo-electric element or cell P with an appropriate shield and normally receiving light from a suitable lamp L focused toward the cell P. The light shining on the cell P enables sufficient current to flow over the track circuit to hold the track relay energized. When a train enters the section it passes between the cell P and light L. The cell P immediately increases the resistance of the track relay circuit, thereby insuring the release of the relay in response to the shunting of the track circuit.

It will be obvious that the photo-electric cell P may, if desired, be employed to control an aux-

iliary relay in the same manner that such a relay is controlled by the microphone M in the disclosure of Fig. 2.

If it is desired to positively insure the dropping 5 of the track relay irrespective of the end of the section entered, this may be accomplished by applying the apparatus at both ends of the track section. In Fig. 8, such an arrangement is illustrated. In this figure an arrangement such as 10 shown in Fig. 6 is modified by including a front contact of the A1 relay in the track feed circuit of the adjoining section B—C. It will be evident then that when a train in section A—B enters section B—C, the auxiliary relay A1 will open 15 the feed circuit to the track relay of section B—C so that the track shunt need be only sufficiently effective to prevent the picking up of the track relay after A1 has ceased to function. The movement of a train from section B—C into 20 A—B will be effective in a manner similar to a corresponding movement as described in connection with Fig. 6, except that as the train leaves the section the A1 relay at the leaving end of the section will hold the track circuit open until 25 the train clears the junction of the adjoining sections.

Although the microphone M is only shown connected in series with the track circuits illustrated by Figs. 1, 3 and 4, and the photo-electric cell P is only shown as employed in the track circuit of Fig. 7, it will be apparent that either or both of these may be included in any of the track circuits shown to increase the release sensitivity of the track relay. Also, although the 35 microphone is only shown in circuit with the A1 relay in Fig. 1, it may likewise as well be included in series with the A1 relay as employed in Figs. 5, 6 and 8.

Although I have herein shown and described 40 only a few forms of apparatus embodying my invention, it is understood that various changes and modifications may be made therein within the scope of the appended claims without departing from the spirit and scope of my invention. 45

Having thus described my invention, what I claim is:

1. In combination, a railway track section; a 50 track circuit for said section including a source of current, a track relay and a current limiting element; a second circuit for said relay including a second source of current and a second current limiting element with the current flow in the reverse direction to that supplied over 55 the track circuit, means included in said second circuit for reducing the current flow therein to the extent required to prevent its interference with the actuation of said relay by current supplied over said track circuit when the section 60 is unoccupied, the current flow over said second circuit becoming effective to aid release of said

track relay when the shunting action of the wheels and axles of a train occupying said section is restricting the current flow to said track relay from said track circuit source, and means including a ground path for varying said reverse 5 current flow in accordance with changes in ground resistance.

2. In combination with a section of railway track and a source of current connected across the rails of the section, a relay having a winding 10 receiving energy from the track rails of the section, a circuit controlling armature adapted to be moved by the force developed by said winding, means for establishing a potential which opposes the normal track potential effective 15 across said winding by an amount such that the resultant potential is sufficient to move said armature when the section is unoccupied, said opposed potential predominating over the normal potential when the section is occupied, and an 20 auxiliary circuit including a ground connection for varying said opposed potential in response to variations in the ground resistance to maintain the unbalanced condition of said potentials constant during changes in weather conditions. 25

3. In combination, a section of railway track, a track circuit for said section including a main source of current and a track relay, means including an auxiliary source in the wayside for passing a current in the reverse direction to that 30 supplied from said main source through said track relay, the magnitude of said reverse current being such that normally the track relay energization from said main source predominates sufficiently to maintain said relay picked up, and 35 means including a ground path for by-passing a portion of the current from said auxiliary source in accordance with variations in the ground resistance whereby when a train enters said section a small reduction in the energization 40 from said main source renders the reverse energization from said auxiliary source effective to release said track relay.

4. In combination, a section of railway track, a track circuit for said section including a source 45 of current and a track relay, an impedance connected across the terminals of said track relay, means for establishing a potential drop across said impedance in the opposite direction to that established by the potential drop due to the track 50 circuit source, the magnitude of the opposed potential drop being such that said track relay is normally maintained energized from said track circuit source, and means including a ground path for varying said opposed potential drop in 55 accordance with changes in ground resistance whereby when a train enters said section and a slight reduction occurs in the normal energization said opposed potential drop will be effective to cause a release of said track relay. 60
